SPRAY GUN

Charles S. Fisher, Detroit, Mich., assignor to
Saylor-Beall Manufacturing Company, a cor-
poration of Michigan

Application April 21, 1932, Serial No. 606,558

2 Claims. (Cl. 299—89)

This invention relates to spraying devices and more especially to spray guns for applying paints, lacquers, enamels, varnishes, oils, insecticides and other liquids, semi-pastes or finely divided materials to desired objects.

The principal object of the invention is to provide an all purpose spray gun that may be used as a pressure or syphon type gun or may be used in conjunction with a pressure feed material tank.

Another object is to provide a gun that may be easily adapted for different purposes by making very simple changes and adjustments.

Other objects and advantages will become apparent from the following description and appended claims.

For the purpose of illustrating the genus of the invention, a typical concrete embodiment is shown in the accompanying drawings in which:

Fig. 1 is a vertical longitudinal section, partially in elevation, through a device constructed in accordance with this invention, the parts of the device being shown in unoperated positions;

Fig. 2 is a top plan view of the device shown in Fig. 1;

Fig. 3 is an enlarged vertical section on line 3—3 of Fig. 1;

Fig. 4 is a horizontal section on line 4—4 of Fig. 1;

Fig. 5 is a vertical section on line 5—5 of Fig. 4;

Fig. 6 is a fragmentary view similar to Fig. 1 with parts in operated position and engaging an adjustable stop means for such parts;

Fig. 7 is a vertical section of a solder bath and illustrating a step in the fabrication of the pressure cup illustrated in Fig. 1;

Fig. 8 is a side elevation, on an enlarged scale, of the material nozzle shown in section in Fig. 1;

Fig. 9 is a vertical longitudinal section, on an enlarged scale of the air nozzle shown in Fig. 1 and illustrating in dot-and-dash line the material nozzle shown in Fig. 8 as these parts are associated in an internal atomizing type of spray gun;

Fig. 10 is an enlarged front elevation of another form of air nozzle of the internal atomizing type.

Fig. 11 is a vertical longitudinal section taken on the line 11—11 of Fig. 10 and showing in dot-and-dash line the material nozzle illustrated in Figs. 8 and 9;

Fig. 12 is a horizontal longitudinal section taken on the line 12—12 of Fig. 11;

Fig. 13 is a view similar to Fig. 10 of another form of air nozzle of the internal atomizing type;

Fig. 14 is a vertical longitudinal section on line 14—14 of Fig. 13;

Fig. 15 is a vertical longitudinal section of an external atomizing type of material nozzle interchangeable with the nozzle of the internal atomizing type shown in Fig. 8;

Fig. 16 is an enlarged front elevation of an air nozzle adapted to be used with the material nozzle shown in Fig. 15;

Fig. 17 is a section taken on line 17—17 of Fig. 16 and illustrating the position of the material nozzle shown in Fig. 15;

Fig. 18 is a section on line 18—18 of Fig. 17;

Fig. 19 is an enlarged front elevation of another form of external atomizing air nozzle adapted for use in connection with the material nozzle shown in Fig. 15;

Fig. 20 is a longitudinal vertical section of the air nozzle shown in Fig. 19 and illustrating in dot-and-dash line the relative position of the material nozzle shown in Figs. 15 and 17;

Fig. 21 is a section on line 21—21 of Fig. 20;

Fig. 22 is a fragmentary enlarged section of the neck portion of the pressure cup, as shown in Fig. 1, and

Fig. 23 is a fragmentary detail of the needle valve operating cams shown in Figs. 1, 2, 4, and 6.

Referring to the drawings, and particularly to Figs. 1 to 6 inclusive, a spraying device is disclosed in the form of a spray gun, which may be used as a pressure type gun, a syphon type gun,

or may be used in connection with a pressure feed material tank. This gun comprises a body member 10 provided with air and material passages, designated 11 and 12, respectively. An intake union 13 is threaded into the rear portion of the body member 10 so as to communicate with the

air passage 11. The union 13 is adapted to have a flexible air line coupled thereto for supplying compressed air to the air passage 11. In this type of gun, air is continually passed through the body member 10 and the volume of air passed therethrough is controlled by the relative adjustment of material and air nozzles 14 and 15 which are concentrically disposed relative to each other and

connected to the forward end of the body member 11 in a manner which will later be more fully described. A downwardly extending cylindrical flange member 16 is formed on the body member 10 and is internally threaded as indicated at 17 so that a pressure cup 18 may be secured thereto.

The body member is provided with a downwardly extending passage 20 communicating between the material passage 12 and the interior of pressure cup 18. A material tube union 21 is threaded within the passage 20 and secures a material tube

22 to the body member 10. The body member is

also provided with passages 23 and 24 which communicate between the air passage 11 and the interior of the cup member, and between the exterior of the body member 10 and the interior of the cup member 18, respectively. The passages 23 and 24 are internally threaded to receive interchangeable plugs 25 and 26, plug 25 being provided with a vent passage therethrough and plug 26 being solid. Interchanging of these plugs converts the spraying device from a pressure type to a siphon type of gun.

Referring particularly to Figs. 4 and 5 the vented plug 25 is disclosed as being positioned in the passage 23, thus providing a vent between the air passage 11 and the interior of cup so that air pressure may be exerted on the top of the material within the pressure cup 18, thus providing a pressure type of spraying gun. In this instance the solid plug 26 closes the vent passage 24 so that no vent is provided between the interior of the pressure cup 18 and the exterior of body member 10. If, however, these plugs are interchanged the vent, afforded by means of the vented plug 25 disposed in the passage 24, is between the interior of the pressure cup 18 and the exterior of the body member 10. With the solid plug 26 closing the passage 23 no pressure will be exerted on the top of the liquid material within the pressure cup 18 from the air passage 11. In the latter instance the gun is arranged as a siphon type spraying device.

The forward end of the material passage 12 is internally threaded to receive complementary threads 27 on the material nozzle 14. The forward end of the body member 10 is provided with a cylindrical flange member 28 which is internally threaded at 30 to receive complementary threads 31 on the nozzle member 15. Thus, means are provided for securing the latter in the desired adjusted position relative to the material nozzle 14 and in concentric relation with respect to the material nozzle. A flange member 28 is also externally threaded to receive a sleeve member 33 provided with a radially disposed flange 34 which cooperates with a flange 35 on nozzle member 15 for locking the nozzle member in adjusted position relative to the material nozzle 14. The air passage 11 communicates with a chamber 36 formed by the flanged member 28, which chamber communicates with the interior of the air nozzle 15. The interior surface of the nozzle 15 and the exterior surface of the nozzle 14 are in the form of converging cones so that the air passing between these nozzles will have an increased velocity as it is discharged through a circular opening 40 at the tip of the air nozzle 15. It is noted that the interior surface 38 merges smoothly with the opening 40 in the tip of nozzle 15, no shoulder being provided on the air nozzle at this point. Nozzle 15 may be adjusted relative to nozzle 14 so as to completely shut off the flow of air between the nozzles, if desired.

A needle valve member 41 is provided in the passage 12 to control the flow of material through this passage and through the material nozzle 14. The needle valve member has a conical tip 42 which cooperates with a complementary seat 43 formed adjacent the tip of the nozzle 14. A bushing 44 is disposed in the rear portion of passage 12, the bushing being retained in position by means of a needle valve packing nut 45 threaded to the rear portion of the body member 10. A packing material 46 is interposed between the bushing and the nut to provide a seal between the needle valve member 41 and the body member 10.

A bifurcated extension member 47 is integrally formed on the rear portion of the body member 10 to provide a support means for the control mechanism for the needle valve member 41. The end of the extension member 47 provides a grip means 48 which is downwardly directed relative to the body member and is disposed in rear of the pressure cup 18. A boss 50 is provided on the top margin of the extension member 47 and a passage is provided in this boss which extends in the direction of the passage 12 with its axis coincident with the axis of the needle valve member 41. The passage 51 is internally threaded to receive the needle valve adjustment screw 52. This screw is centrally bored as indicated at 53 to receive the needle valve spring 54. The needle valve member 41 is threaded at the rear end thereof to receive the needle valve adjustment screw stop member 55 and a lock nut therefor designated 56. The stop member 55 is machined slidably to fit the bore 53 of the needle valve adjustment screw 52 and a shoulder 57 is provided on the forward end of stop member 55 to engage the forward end of the adjustment screw 52.

In the above arrangement the spring 54 normally biases the needle valve member 41 into engagement with the seat 43 in the material nozzle 14. The adjustment screw 52 provides means for stopping the rearward stroke of the needle valve member 41 at any desired point.

The means for controlling the rearward stroke of the valve member 41 to control the amount of material passing through the passage 12 comprises a trigger member 60 in the form of a bell crank pivoted to the extension member 47 by means of a bearing pin 61. One arm 62 of the trigger member 60 is provided with a cam surface 63 and the other arm 64 is provided with a finger piece 64. A pair of trigger cams 65 is also pivoted to the extension member 47 on the bearing pin 66 and one arm of each trigger cam is provided with a bearing surface 67 on one arm and a second cam surface 68 on the other arm. The trigger and trigger cams are so arranged that the cam surfaces 68 engage the lock nut 56 so that pressure on the finger piece 64 causes rearward movement of the needle valve member 41. The cooperating cam surfaces 63 and 67 are so arranged that, upon initiation of movement of the trigger finger piece 64, the arms of the trigger and trigger cams are essentially equal, however, as movement of the finger piece 64 continues, the arm 62 of the trigger lengthens and the cooperating arms of the trigger cams 65 shorten so that cams 68 move rearwardly at a progressively increasing rate relative to the rearward movement of the finger piece 64. Thus upon the initiation of the rearward movement of the finger piece 64 the maximum sensitivity of adjustment of the needle valve 41 is obtained. Upon continued rearward movement of the finger piece 64 the control of the needle valve member is less sensitive and the needle valve member is moved rearwardly at a faster rate. The maximum sensitivity of control of the needle valve is desirable at the initiation of the movement of the trigger for decorative or fine work such as lining or work close to the margin of a different color. It is also desirable to provide means for effecting a quick opening to the valve so that slugs of material in the nozzles of the gun may be cleared out by a sudden blast of material therethrough. The control mechanism above described, satisfies both requirements. It is noted that in the present construction, which provides two trigger cams 75

65 separated by a spacer 69, that one cam surface 68 bears against the lock nut 56 with a greater pressure than does the other cam surface 68, and that rolling contact between the trigger cam 5 which exerts the greater pressure of the needle valve member 41 causes rotation of this valve member. The trigger cams 65 are in the form of bell cranks and the lowermost of the two trigger cams as viewed in Figs. 2 and 4 has the legs thereof, which carry the cams 67 and 68, disposed at a slightly smaller angle with respect to each other than the angle formed by the corresponding legs of the uppermost trigger cam. Since both trigger cams are rotated about the pivot 66 in a clockwise direction by the same cam surface 63, the lowermost trigger cam 65 will exert the greater pressure on the lock nut 56 while the uppermost trigger cam will bear but lightly on the lock nut or even may be slightly spaced therefrom. As viewed in Fig. 2, the trigger cam 65 adjacent the bottom of this figure, preferably exerts the greater pressure, since this will at all times tend to keep the lock nut 56 secured against the needle valve stop member 55. The rotation 25 of the needle valve member 41 by the trigger cams 65 upon operation of the needle valve member will cause its tip 42 to grind into and out of the valve seat 43 thus keeping the tip 42 and seat 43 free from the material being dispensed and keeping 30 the surfaces, valve tip and valve seat ground so as to make full contact to insure complete closure of the material passage 12. The double cam lever construction permits a lowered disposition of the handle and shielding of the major part of 35 the moving element by the gun and pressure can. This makes the cleaning of the gun easier. In operating the needle valve it is to be noted that the resistance of the trigger is practically constant and that spring 54 is always compressed to 40 the same extent at the limit of the rearward movement of valve 41 regardless of the position of adjustment screw 52. It is also noted that valve 41 may be disassembled from the gun by simply unscrewing adjustment screw 52 from boss 50 45 without any other disconnection of the valve from its control mechanism.

Referring particularly to Figs. 1, 3, and 4 it will be noted that the material nozzle 14 has a hexagonally cut collar 70 integral therewith of a size 50 such that it will fit closely the interior of the air nozzle 15 and at the same time permit free passage of air along the flats of this collar from the air passage 11 to the space between the material and air nozzles. It is also noted that immediately forward of the collar 70 the material nozzle 14 has diametrically opposed cuts 71 so that the material nozzle may be turned into the body member 10 to effect a seal between these members.

60 Referring particularly to Figs. 1 and 7, the construction of the pressure cup will be described. It has been the usual practice to construct these cups of aluminum with the threads rolled into the neck portion thereof and a bulge extending inwardly into the bottom of the cup. In order to roll the threads into the neck portion thereof and to provide an inwardly directed roll at the end of the neck portion to obtain a square end surface relative to the threads so that the cup may engage squarely against the gun portion, it has been necessary to make the cup of relatively thin material. With this thin material the bottom portion of the pressure cup was the least able to withstand the internal pressure in the cup and 70 outward bulging of the bottom portion resulted 75

when slugs were caught in the nozzles of the gun. Internal reinforcements of the bottom bulge of the cup have been attempted but since air gets between these reinforcements and the cup bottom the effect is lost. Outside reinforcements also have been attempted but as this mars the appearance of the cup, this expedient has not been brought into extensive use. In rolling the threads into the neck portion of the head it is practically impossible to get the end of the neck portion of the cup square with the threads. In such a construction the end of the neck portion is usually rolled inwardly to get a smooth edge for the gasket interposed between the cup and the gun and it has sometimes been attempted to machine the ends, however, this causes a very large percentage of scrapped cups, since because of the thinness of the material, the cutting often projects through the end of the rolled portion. This also develops in a wide bearing portion at the 20 end so that a large force must be employed to effect a seal between the cup and gun or to unscrew a cup from the gun portion.

In the present construction the pressure cup 18 is made of two parts, namely a collar member 73 25 and a heavy sheet copper container member 12 having an inwardly directed bulge portion at the bottom thereof and a cylindrical neck portion at the upper end. A collar member 73 is turned from solid material, such as brass, the collar having threads 74 cut thereon and a sharp edge 75 machined at the top edge thereof cut square with respect to the threads so that an effective seal between the cup and gun may be obtained. In securing the collar 73 to the container member 12 30 the collar is placed on the neck portion thereof and the upper margin of the neck is pressed outward slightly to position the collar relative to the container. The neck portion of the container with the collar thereon is then dipped in a solder bath 69 as indicated in Fig. 7 to effect a solder connection between the neck portion and the collar, and also to give the exterior surface of the threads 74 a babbitt surface or plating 76. The babbitt surface or plating 76 on the thread 74 35 offers the minimum of friction between the threads of the collar and of the gun proper, so as to afford ease of operation and freedom from sticking when the pressure cup and gun are assembled and disassembled. The gasket 78 is interposed between the ends of the pressure cup and the body portion of the member 10. A cup of the above construction will withstand an internal pressure of 75 pounds per square inch without causing an outward bulging of the bottom thereof. In the two piece construction of the pressure cup the container may be made of much thicker material than in the case of the one piece cups having threads rolled therein, so the two piece cups may be made to withstand any desired 40 internal pressure without causing a deformation of the bottom thereof.

Referring particularly to Figs. 8 and 9 the internal atomizing type of nozzles are shown which are preferably machined from brass and chromium plated. These nozzles are the same as illustrated in Figs. 1 to 4 inclusive.

In Figs. 10 to 12 inclusive, internal atomizing nozzles are shown which are similar to those previously described except that a slot 81 is 70 provided in the tip of the air nozzle 15 instead of the circular opening 40 disclosed in the previous embodiment. This slot 81 flattens the spray delivered by the gun so that a thinner and more uniform application of the material to be 75

dispensed may be made. It is noted that the interior surface 37 of the air nozzle 15 merges smoothly with the slot 84 and that no shoulder is provided at this point. It has been found that better atomization of the material to be dispensed is obtained when no shoulder is provided on the air nozzle adjacent the circular or slotted openings therein.

In the nozzles shown in Figs. 13 and 14, a slot 10 82 is provided in the tip of the air nozzle 15 which is disposed at an angle with respect to the axes of the material and air nozzles and somewhat to the side of said axes. This inclination of the slot in the tip of the air nozzle is 15 provided so that the gun is more readily adapted for application of material to horizontal surfaces disposed above or below an operator, such as ceilings and floors. In applying material to surfaces such as ceilings, the nozzle would be adjusted to the position shown in Fig. 13 and in applying it to surfaces such as floors, this nozzle would be rotated to a position at an angle of 180 degrees from that shown in Fig. 13. It is to be noted that in this instance also, the interior 20 surface 37 of the air nozzle 15 merges smoothly with the margins of the slot 82 so that no shoulder is provided adjacent the tip of the nozzle 15.

In the nozzles disclosed in Figs. 9 to 14 inclusive, it is noted that in each instance the interior surface of the air nozzle and the exterior surface of the material nozzle comprise converging cones which increase the velocity of air as it passes between these nozzles. This effects very 30 complete atomization of the material dispensed.

In Figs. 15 to 18 inclusive the external atomizing type of nozzles are disclosed. These nozzles are preferably machined from brass and nickel plated. These nozzles are interchangeable with 40 the internal atomizing type of nozzle previously described. The material nozzle 84 and air nozzle 85 in the present instance, however, are made blunter at the tip than in the case of the internal atomizing type of nozzle above described.

45 The exterior surface 88 of the material nozzle 84 and the interior surface 87 of the air nozzle 85 are inclined at a greater angle with respect to the axes of the nozzles than in the case of the internal atomizing type and comprise converging cones to increase the velocity of the air as it passes between the nozzles, as in the previous 50 embodiments. The material nozzle 84 is provided with a cylindrical extension at the forward end which is adapted to project through a circular opening in the tip of the air nozzle 85. The extension extends slightly beyond the opening, however, this member should not extend more than $\frac{1}{2}$ of an inch beyond the end of the air nozzle 85. The nozzle 85 is secured to the 55 body member 10 of the gun by means of a flange corresponding to the flange 35 of the nozzle 15 shown in Fig. 4 and the sleeve ring 33 shown in Figs. 1, 2, and 4.

In Figs. 19 to 21, inclusive, a slightly different 60 type of external atomizing nozzles is disclosed. In this type, the air nozzle 95 has diametrically opposed extensions 96 provided on the sides thereof, which are in turn provided with passages 97 which direct air inwardly against the spray 65 discharged from the nozzles so as to flatten the spray. These passages 97 communicate with the space between the material and air nozzles so as to receive air therefrom for flattening the spray.

70 75 In use, the internal atomizing nozzles are used

for slow drying materials, such as paints and varnishes, in which instance, air pressure is required on the material in the pressure cup. When using the internal atomizing nozzles, the interchangeable plugs 25 and 26 are positioned 5 as disclosed in Fig. 5. The external atomizing type of nozzles are used for fast drying materials, such as lacquers, synthetic enamels, etc. In using the external atomizing nozzles, no pressure is exerted on the material within the pressure cup since the side stream of air cannot break up the spray fast enough. Instead, the spraying device is used as a syphon type gun, in which instance, the positions of the interchangeable plugs 25 and 26 are reversed with respect 10 to the positions shown in Fig. 5, so that the passage 23 is closed and the vent passage 24 is opened from the cup interior to the atmosphere.

When the spraying device is employed in connection with a pressure feed material tank, the 20 tube 22 and pressure cup 18 are removed from the spraying gun. A flexible hose from the pressure tank may be connected to the passage 20 to apply the material to be dispensed. The interchangeable plugs 25 and 26 are arranged in 25 the same manner as in the case of the syphon type gun and either the internal atomizing or the external atomizing type of nozzles may be employed, however, when using the external type, a regulator is employed in connection with the 30 pressure feed material tank to lower the pressure at which the air is delivered thereto.

It is noted that the tube 22 is provided with a bend so that it may extend to either the forward portion of the bottom of the pressure cup 35 as disclosed in full lines, or adjacent the rear portion of the bottom of the pressure cup as disclosed in dotted lines, in Fig. 1. This is to permit withdrawal of practically all of the material within the pressure cup when the nozzles 40 shown in Figs. 13 and 14 are employed. When applying material to a horizontal surface, such as a floor, the tube 22 is positioned as shown in full lines in Fig. 1, and when applying material to a horizontal surface, such as a ceiling, the 45 tube is positioned as shown in dotted lines in this figure.

As many changes could be made in the above 50 described arrangement, and many apparently widely different embodiments of this invention could be made without departing from the scope thereof, it is intended that all matter contained in the above description or showing shall be interpreted as illustrative and not in the limiting sense.

55 What is claimed is:

1. A spraying device comprising a body member 60 provided with material and air passages therein, valve means for closing said material passage, means for operating said valve to regulate the flow of material through said material passage, a pressure cup removably secured to said body member, a conduit member secured to said body member and communicating between said material passage and the interior of said 65 pressure cup, said body member being provided with other passages, one passage communicating between said air passage and the interior of the pressure cup and another passage communicating between the exterior of said body member 70 and the interior of the pressure cup, and means for closing either of said two last-named passages for selectively converting the spraying device from a syphon type to a pressure type of spraying device.

2. A spraying device comprising a body member provided with material and air passages therein, valve means for closing said material passage, means for operating said valve to regulate the flow of material through said material passage, a pressure cup removably secured to said body member, a conduit member secured to said body member and communicating between said material passage and the interior of said pressure cup, said body member being provided with other passages, one passage com-

municating between said air passage and the interior of the pressure cup and another passage communicating between the exterior of said body member and the interior of the pressure cup, and interchangeable plugs for said two last-named passages, one of said plugs being solid and the other provided with an opening therethrough whereby said spraying device may be converted from a syphon type to a pressure type of spraying device by interchanging said plugs. 10

CHARLES S. FISHER.
